UNITED STATES PATENT OFFICE.

JAMES CAMILLE ROSSI, OF PERTH AMBOY, NEW JERSEY, ASSIGNOR, BY MESNE ASSIGNMENTS, TO JOHN T. FARGASON, OF MEMPHIS, TENNESSEE.

MACHINE FOR MANUFACTURING ICE.

SPECIFICATION forming part of Letters Patent No. 397,819, dated February 12, 1889.

Application filed June 9, 1888. Serial No. 204,578. (No model.)

To all whom it may concern:

Be it known that I, JAMES CAMILLE ROSSI, of Perth Amboy, in the county of Middlesex and State of New Jersey, have invented certain new and useful Improvements in Machines for Manufacturing Ice, of which the following is a specification, reference being had to the accompanying drawings.

My improvements consist of apparatus working upon the general principle and operating in accordance with the method set forth in my United States patent, No. 300,138, dated June 10, 1884, so far as the idea of continuous action is concerned.

My object is to produce a simple, economical, convenient, and continuously-operating apparatus, which may be of varying sizes and capacity, to be used mainly for the manufacture of ice.

I provide a series of contiguous tubs or vessels of any desired form, but as represented in the drawings, and as I think generally preferable, of circular form, one surrounding another, the central one being the freezer, and the others, whether one, two, or more, I term the "economizers." The structure is such that I keep up a continuous supply of water, under pressure, that is cooled in the economizers on its way to the freezer, where a proper chemical salt for reducing the temperature by being dissolved is supplied with practical continuity. The discharge of the impure water, or that which has been impregnated with the salt from the freezer, is by overflow to the first economizer and then to the other or others, and finally out of the last as a waste solution to evaporators or suitable condensers.

In the accompanying drawings, illustrating my improved apparatus, Figure 1 is a vertical central section, and Fig. 2 is a horizontal section on the line 2 2 of Fig. 1.

Referring to the letters upon the drawings in aid of a detailed description of this particular form of the apparatus, which I deem the best form of this peculiar machine, A indicates the freezer, which is a central cylindrical vessel made of wood or paper pulp, for the sake of lightness, cleanliness, and non-action of the solution on the material.

B and C are economizers, being cylindrical vessels surrounding the freezer, and of similar material, and containing coils F F'. These three vessels are carried on the platform U, movable, for convenience, on wheels U' U'. 55 Pipes Y are provided at the bottom for emptying these vessels through a cock or valve, Y'.

The freezing-vessel A may be provided with a perforated false bottom, L, of similar material to that of the vessel. At the upper part 60 of the interior of the vessel A are projections b b, which are arcs of a circle and constitute the support or bearing of the can-holder R, which is simply a support of wood with apertures, into which are inserted the cans N N, 65 containing water to be frozen. These may be of any desired form, and are held in place by projections P near their tops, and provided with covers Q, preferably of wood.

M indicates the salt-feeder, which passes 70 through the cover of the apparatus, through the can-holder, and down through the vessel A, and rests upon a block or socket, M'. It is a hollow cylinder of tin or paper or wood-pulp, perforated along its lower part by 75 numerous large holes, O, and carrying at the top a hopper or a funnel, as shown. This salt-feeder is made fast to the can-holder by any suitable means, such as plates and screws X'.

W W indicate parts fixed to the upper part 80 of the salt-feeder above the cover of the apparatus, provided with handles S, by means of which the salt-feeder, and with it the can-holder R and cans, can be oscillated to agitate the liquid in the vessel A.

An opening, p, is provided for the overflow from the vessel A into vessel B, and an opening, n, is provided for overflow from the vessel B into the vessel C, which latter overflows by means of the pipe m' into evaporators or 90 vessels. (Not shown.)

The feed-water is supplied from a reservoir or hydrant, D, under pressure. It flows through the pipes E E into coil F' in vessel C, and reaching the connection G into the coil F of 95 vessel B, and from there by the pipe H, provided with a valve, V, through the pipe K, preferably surrounded by an envelope of paper-pulp, K', to prevent the freezing of water in the pipe. From the pipe K the water is 100

delivered downward into the vessel A beneath the false bottom L, as indicated by the arrows. When the feed-water strikes the salt charged at the start in freezer A through salt-feeder 5 M, it dissolves the salt, producing an intense cold, which, being transmitted to the ice-cans N, freezes the water they contain, or, more properly speaking, absorbs the heat of the water they contain, so as to congeal it. The 10 level of the solution in A soon rises to the level of the overflow-opening p, and the cold brine of the vessel A begins to fill the annular vessel B, cooling the water flowing in the coil F. In its turn the solution of the vessel 15 B, receiving constant influx from vessel A, overflows into vessel C, and further cools the feed-water flowing through coil F of vessel C. Finally the solution overflows from vessel C through pipe m' to evaporators, or to 20 be utilized to cool distilled water for drinking purposes in a water-cooler, or for cooling water to be used to fill ice-cans, or for any other cooling purpose. As the cold water dissolves the salt contained in vessel A and in the 25 lower part of the salt-feeder tube M, the salt drops in the salt-feeder M by gravity, taking the place of that which has been dissolved. More salt is supplied as the hopper is emptied, and the process of freezing continues in 30 the cans N.

A trap or regulator, T, of ordinary kind, may be provided to regulate the feed of the salt from the hopper into the tubular part of the salt-feeder. By a proper regulation of the 35 admission-valve V on the feed-water pipe H and of the delivery-valve X of the reservoir or hydrant D, it is easy to provide a proper supply and flow of water, and salt can be supplied, so that the freezing will continue 40 constantly, the only interruption being the removal of the ice made and the replacing of the cans N filled with pure water for freezing. It is not necessary to agitate the freezing-solution in vessel A; but the operation of 45 freezing will be promoted by so doing. It is not absolutely necessary to employ the false bottom L, but generally desirable.

The lower end of the pipe K might be in the form of a nozzle or sprinkler to divide the 50 inflow of feed-water to vessel A into numerous jets.

I do not confine my invention to the precise form of apparatus shown, because various 55 formal changes might be made. For example, coils F F' are merely provided to give a greater extent of flow of the water-supply and more time for cooling; but any other form of pipe

F might be adopted, although I think coils preferable. The vessels or tubs (freezer and economizers) might be contiguous and not concentrical to each other. They might be put in line close together and one after the other, or in the shape of a triangle, if two economizers be used, or of a rectangle if three 60 economizers be used; but the concentric form 65 is generally preferable. The mode of operation in any of these dispositions is substantially the same.

Of course it will be understood that the water at first inflowing will not be cooled until 70 it reaches the freezer, the special cooling operation of the inflowing water only beginning outside of the freezer after it has been filled and the overflow has commenced; but in practice this is immediately after the operation 75 begins, so that very soon the water that comes in contact with the salt to be reduced in temperature will have been already materially reduced in the economizers, so that the salt in the freezer does its work with great 80 perfection. Of course a cold solution might be placed in the economizers before the inflow commences, and this may be done whenever desired.

Having thus described my machine, what I 85 claim as new, and desire to secure by Letters Patent of the United States, is—

1. In an ice-machine, the combination of the freezing-vessel A, provided with the can-holder R, resting upon supports b and adapted 90 to be oscillated, the salt-feeder secured to the can-holder and provided with handles S, the block M', for supporting the lower end of the can-holder in its socket, so that the oscillation of the can-holder and cans can be effected, 95 substantially as set forth.

2. In an ice-machine, the combination of a central freezing-vessel A, provided with a can-holder, R, resting upon supports b and adapted to be oscillated, the salt-feeder secured to the can-holder and provided with handles S and block M' and surrounded by vessels B C, containing coils F F', the latter being continuations of the water-supply pipe and terminating in the pipe K at the bottom 100 of the freezing-vessel A, with the overflow-outlets p, n, and m, substantially as set forth.

In testimony whereof I have hereunto subscribed my name.

JAMES CAMILLE ROSSI.
